ELECTRIC GRASS TRIMMER

Roderick F. Bunyea, Cockeysville, Md., assignor to The Black and Decker Manufacturing Company, Towson, Md.

Filed July 24, 1970, Ser. No. 24,116

Term of patent 14 years

Int. Cl. D8—01

U.S. Cl. D8—8

United States Patent Office

Des. 221,507

Patented Aug. 24, 1971

FIG. 1 is a perspective view of the electric grass trimmer showing my new design, the broken line being for illustrative purposes only;

FIG. 2 is a plan view showing the electric grass trimmer of FIG. 1 with the handle broken away, for convenience of illustration;

FIG. 3 is a side elevational view of the electric grass trimmer of FIG. 2;

FIG. 4 is an elevational view of the opposite side of the electric grass trimmer of FIG. 2;

FIG. 5 is a rear elevational view of the electric grass trimmer of FIG. 2; and

FIG. 6 is a front elevational view of the electric grass trimmer of FIG. 2.

I claim:

The ornamental design for an electric grass trimmer, as shown and described.
